SWITCH FOR DEVICES FOR SUPPLYING PAPER TO PRINTING PRESSES

Filed July 28, 1927

UNITED STATES PATENT OFFICE

JAMES E. RUST, OF PARK RIDGE, ILLINOIS, ASSIGNOR TO GUSTAVUS A. E. KOHLER, OF CHICAGO, ILLINOIS

SWITCH FOR DEVICES FOR SUPPLYING PAPER TO PRINTING PRESSES

Application filed July 28, 1927. Serial No. 209,030.

This invention relates to switches for devices for supplying paper to printing presses and has for its object to provide a new and improved device of this description.

5 The invention has as a further object to provide a push button switch of this description for introducing current into the solenoid of an electromagnetic switch.

10 The invention has further objects which are more particularly pointed out in the accompanying description.

Referring now to the drawings, Fig. 1 is a plan view of one form of switch embodying the invention.

15 Fig. 2 is a sectional view taken on line 2—2 of Fig. 1.

Fig. 3 is a sectional view taken on line 3—3 of Fig. 1.

20 Like numerals refer to like parts throughout the several figures.

Referring now to the drawings, the switch consists of a base 1 of insulating material adapted to receive two contact devices connected with the base and the opposing spring contacts 2 and 3 and 4 and 5.

25 These contacts are preferably arranged in grooves in the base. The base is provided with the holes 6 for the screws 7 which pass through the spring contacts to hold them in position. The holes 6 are enlarged at the lower ends and are provided with shoulders 8 for the heads of the screws 7. These screws also pass through the terminals 9 for the conductors 10 running to the solenoids. The conductors 10 are held in the terminals 9 by the screws 11 which pass therethrough and through the spring contacts. These screws project into openings 12 in the base, the openings being larger than the screws as shown.

30 The spring contacts 2 and 3 are electrically connected by a movable contact 13 and the spring contacts 4 and 5 are electrically connected by the contact 14. These contacts are connected with push rods 15 and 16 by means of screws 17 which work in screw threaded openings in the push rods. The openings for these screws are enlarged at the end at 17^a there being no screw threads at that point. This allows clearance for the screw. There is a possibility of the contacts being loosened

by turning when engaging the spring contacts. To prevent this the push rods are crimped at their ends as shown at 17^b.

The push rods are of insulating material. The contacts 13 and 14 are larger than the openings in the base at the points where they are located so that their movement in one direction will be stopped by the base. The push rods are provided with the push buttons 19 and 20. The push rods are preferably 55 roughened as shown at 17^c so as to insure a better connection with the push buttons. The contacts 13 and 14 are normally held in their inoperative positions, that is, away from the spring contacts 2, 3, 4, and 5 by springs 21 and 22 which are enclosed in the base 1. The springs at one end engage the shoulders 23 and 24 and at the other end, the push buttons. 60

65 It will be seen that when the push buttons are pressed, the contacts 13 and 14 will be moved to connect the spring contacts 2 and 3 and 4 and 5 and thus complete the circuit through the device with which the conductors 10 are connected. When the push buttons are released, the springs move the contacts 13 and 14 out of engagement with the spring contacts, thereby breaking the circuit. 70

75 I claim:

1. A device of the kind described comprising a base of insulating material, said base having two flat portions and a projection between said flat portions, opposed separated spring contacts connected with the flat portions of said base and extending along said projection, the ends thereof projecting beyond said projection, a third contact movably connected with said base adapted to electrically connect the spring contacts and means for automatically disconnecting the third contact from the spring contacts when the contact is released. 80

85 90 95 100 2. A device of the kind described comprising a base of insulating material having a projection with a flat portion on each side thereof, opposed spring contacts connected with said flat portion and extending along said projection, said projection being provided with an opening, said contacts having their separated ends in proximity to said opening, a push rod in said opening, a contact connected with the

end of said push rod adapted, when the push rod is moved in one direction to electrically connect said spring contacts and a retracting device for said push rod, said contact projecting laterally beyond the push rod and acting as a stop to limit the movement of the push rod responsive to the retracting device.

3. A device of the kind described comprising a base having a projection with a flat portion on each side thereof, opposed spring contacts connected with said flat portion and extending along said projection, said projection being provided with an opening, said contacts having their separated ends in proximity to said opening, a push rod of insulating material in said opening, a contact removably connected therewith adapted, when the push rod is moved in one direction to electrically connect said spring contacts, said push rod being at all times out of contact with said spring contacts, a push button connected with said push rod and a retracting spring surrounding said push rod.

4. A device of the kind described comprising a base having a projection with a flat portion on each side thereof, two sets of spring contacts connected with said flat portion and extending along said projection, said projection being provided with two openings one in alignment with each set of spring contacts, push rods in said openings, each comprising a central portion of insulating material and a separate enlarged end of insulating material, conducting contacts connected with said push rods, said contacts at all times exterior to said base and acting as stops to limit their movement away from the spring contacts and adapted when moved outwardly to electrically connect said spring contacts, and means for automatically disconnecting the contacts and the spring contacts when said spring contacts are released, comprising a spring surrounding the central portion of each push rod, one end of each spring engaging the enlarged end of the push rod, the other end engaging the base.

5. A device of the kind described comprising a base having an opening extending therethrough, two separated shoulders on the interior of said base at different points along said opening, a push rod in said opening, a spring surrounding said push rod and engaging one of said shoulders, a push button larger in diameter than said rod and connected with the end thereof, said push button adapted to engage the other shoulder when pushed inwardly to limit the inward movement of the rod in one direction, a contact connected with the end of said push rod and located outside of the base and engaging the same when the push button is released to limit the movement of the rod in the other direction, and separated spring conductors adapted to be en-

gaged by said contact when it is moved to a predetermined position.

Signed at Chicago, county of Cook and State of Illinois, this 8th day of July, 1927.

JAMES E. RUST.
